Attorney.

UNITED STATES PATENT OFFICE.

FRANK DOCHNAL, OF ST. LOUIS, MISSOURI.

MANUFACTURING OF HOLLOW TILE AND THE LIKE.

1,348,932.

Specification of Letters Patent. Patented Aug. 10, 1920.

Application filed October 28, 1918. Serial No. 259,921.

To all whom it may concern:

Be it known that I, FRANK DOCHNAL, a citizen of the United States, residing in the city of St. Louis and State of Missouri, have invented certain new and useful Improvements in the Manufacturing of Hollow Tile and the like, of which the following is a specification.

My invention relates to the manufacture 10 of hollow tile and the like, by means of machines adapted to press or force the soft clay through forming dies to give the tile the proper shape, and more particularly the invention relates to rotatable means for 15 perforating and grooving a wall or walls of a hollow building tile for wall structures, building tile for partitions, or building copings and the like.

One object of perforating and grooving 20 the body of a tile is to permit the ends of the tile to be easily removed after burning, where it is desired to use open ended tile.

A further object of the invention is to provide one or more walls of the tile with 25 perforations so that the tile may be used for partitions to which plaster may be applied and adhere.

A further object of the invention is to 30 position the perforating or grooving means adjacent the mouth of a die and in the path of travel of the tile leaving the die so that the forward movement of the tile will impart a rotary movement to the perforating and grooving means.

35 My invention will be more readily understood by reference to the accompanying drawings, forming a part of this specification, and in which:

Figure 1, is a front elevation of a forming 40 die showing my invention applied thereto.

Fig. 2, is a top plan view thereof, with portions broken away and showing the clay being forced through the die for shaping it into hollow tile.

45 Fig. 3, is an end elevation of a hollow tile after it has been formed, showing one of the end walls provided with a plurality of lines of alternate perforations and grooves to permit the end walls of the tile being 50 easily broken out or removed when open ended tile is desired.

Fig. 4, is a sectional view of one end of a tile taken through the perforations and grooves.

55 Fig. 5, is a fragmentary end view of a tile

showing a part of one of the end walls broken away.

Fig. 6, is a side elevation of a partition tile showing one of its walls provided with a multiplicity of perforations or openings 60 which will permit plaster to enter the openings and adhere to the tile.

Referring to the accompanying drawings the reference character 1 designates a suitable clay receiving die while 2 designates 65 the forming head thereof. 3 represents the soft clay, 4 the plunger for forcing the clay through the forming die and 5 a part of the formed tile as it is leaving the forming die.

In carrying out the aim of my invention, I employ a plurality of perforating and grooving elements having the hub portions 6. The periphery of each hub is adapted to contact with the outer face of the tile to 70 assist in setting the perforating and grooving elements into motion. These elements are each rotatably mounted upon a suitable bracket 7, preferably, although not necessarily supported by the forming die. 75

In the drawings, I have shown for convenience only, three rotary elements on each side of the forming die 2 and each element is provided with a plurality of relatively long radial extending perforating arms 8 85 and intermediate each pair of arms 8 a relatively short groove forming arm 9.

It is obvious that the moving clay tile will 90 impart a rotary movement to the elements 6 as the tile is pushed forward and that the arms 8 and 9 of each element 6 will perform its duty of perforating and grooving the end walls of the tile. The end wall or walls of a tile, so perforated and grooved may be 95 easily removed, or broken out by a slight tap with a hammer or other tool. Open end tile must have some means to prevent the side walls of the tile from warping while being burnt, thus providing the tile initially with end walls which are provided 100 with a plurality of lines of perforations 10 and grooves 11, alternately arranged, permits the end walls to be easily and quickly removed after being burnt, as is manifest.

It will be here understood, that I may 105 provide the face or faces of a tile with a line, or lines of perforations 10 only, if so desired, and omit the grooves 11, or vice versa. It will also be understood that for partition tile designated 12, as shown in Fig. 110

5, I may provide one or more walls with a multiplicity of perforations or openings 13 through which plaster may pass in order that it may positively adhere to the face of 5 the tile.

When perforations only are wanted, in the wall of a hollow tile or other article, the rotary perforating elements are only provided with the long arm 8, which will pass 10 completely through the wall of the tile, as is manifest, and, where grooves only are desired the short arms 9 only, are used on the rotary elements 6.

If desired, the rotary perforating or 15 grooving elements may be power driven at a speed to correspond to the travel of the tile being formed.

The perforations, or grooves, or both, may be formed in the wall or walls of a tile in 20 straight lines, staggered or in any other manner desired. The perforations may be of any size, or shape, likewise the grooves.

It will be understood that as many rotary elements 6 may be employed, as desired, and 25 that one or all four walls of a tile may be perforated or grooved at the same time, as is manifest.

The many advantages of the herein described invention will readily suggest them-

selves to those skilled in the art to which 30 it appertains.

I do not desire to be understood as limiting myself to the details of construction and arrangement as herein described and illustrated, as it is manifest that variations and 35 modifications may be made in the features of construction and arrangement in the adaptation of the device to various conditions of use without departing from the spirit and scope of my invention and the terms of 40 the following claim, hence wish it to be understood that I reserve the right to make any such changes or modifications as may fairly fall within the scope of the appended 45 claim when fairly construed.

What I claim is:

The combination, with a tile forming die, of a rotary perforating and grooving means adapted to be set in motion by the tile leaving the forming die comprising radially extending arms perforating means, radially extending grooving means and a hub arranged on each side of said perforating and grooving means adapted for peripheral contact with the tile leaving the forming die. 50 55

In testimony whereof, I have hereunto signed my name to the specification.

FRANK DOCHNAL.
